UNITED STATES PATENT OFFICE.

WILLIAM JAMISON CURRY, OF VANCOUVER, BRITISH COLUMBIA, CANADA.

ARTIFICIAL DENTURE.

1,128,664.

Specification of Letters Patent. Patented Feb. 16, 1915.

Application filed March 21, 1914. Serial No. 826,377.

To all whom it may concern:

Be it known that I, WILLIAM J. CURRY, a citizen of the Dominion of Canada, residing at Vancouver, in the Province of British Columbia, Canada, have invented certain new and useful Improvements in Artificial Dentures, of which the following is a specification.

This invention relates to an improved means for attaching an artificial tooth to a metal backing on which it is mounted, and is applicable to either plate, bridge, or individual crown work, the object being to simplify the manner of attachment and to enable the tooth to be removable for change or repair.

The invention is particularly described in the following specification, reference being made to the drawings by which it is accompanied, in which:

Figure 1 is a perspective view to an enlarged scale of a single tooth attachment. Fig. 2 is a similar view of an artificial molar tooth as prepared for attachment. Fig. 3 is a sectional plan of a tooth with the crown removed. Figs. 4 and 5 show a perspective and sectional plan of three teeth mountings as attached together to form a bridge, and Fig. 6 is a side elevation showing the attachment as applied to an individual crown.

The device comprises the combination with a tooth body 5 having a groove 6 on each side, of a back plate 2 having sides 3 forwardly bent from it, the edges of which sides are inwardly bent, as at 4, to fit the grooves 6 of the tooth body. Preferably the lingual face of the tooth body is tapered from the larger dimension at the crown to the smaller dimension at the neck in which case the grooves 6 should be substantially parallel to the front face of the tooth and the sides 3 of the metal backing are correspondingly triangular so that when the tooth body is inserted between the sides 3 with the inwardly turned edges in the grooves 6 as the tooth is pressed down it will wedge itself tightly against the back plate 2. Within this backing the tooth body is cemented.

Fig. 6 shows the application of this attaching device to an individual crown: Before the tooth body 5 is placed in position, the retaining plate 2, 3, 4 is strongly soldered, as at 7, to the cap plate 8 of the root, and the tooth body 5 is thereafter cemented and pressed tightly into position.

Where the device is applied to bridge work, the sides 3 of the attaching plates are soldered together at 9, as shown in Figs. 4 and 5, for the effective soldering of which the sides 3 offer an ample area, and they are thereafter strongly soldered to the abutment attachment.

In the case of plate work, the lower edges of the back plates 2 are strongly soldered to the edge of the plate and the sides 3 to one another.

As shown in Figs. 3 and 5, the width of the tooth body, where it passes between the side plates 3, may be reduced by the thickness of the plate 3 on each side and the soldering, so that the sides of the teeth 5 may be brought close together and avoid exposure of the gold or other metal of the attachment.

It will be seen that the attachment as here set forth is not only a particularly simple and convenient one to manufacture and use, but it affords facility for the removal of any tooth for change or repair. Further, the required soldering may be done before the teeth are inserted so that there is no risk of the teeth being fractured during the work of soldering.

The teeth are not only supported and strengthened by the metal of the back but the depth of the back plates with the teeth in position also forms a particularly strong structure for both bridge or plate work.

Having now particularly described my invention, I hereby declare that what I claim as new and desire to be protected in by Letters Patent, is:

1. An artificial tooth attachment, comprising in combination, a tooth body the back of which is flat and extends from the back edge adjacent the attrition surface forward toward the front at the cervical end, each side of the tooth having a groove adjacent and substantially parallel to the front face of the tooth body, the sides of the tooth to the rear of said grooves being parallel plane surfaces, and a plate of thin sheet metal fitting against the flat back and the sides of the tooth, the front edges of the sides of the metal plate being bent inward to fit the grooves, and means for attaching this fastening to the structure by which the tooth is supported in the jaw, all being arranged whereby when two or more tooth attachments are brought into juxtaposition side by side, the abutting sides of adjacent

attachments will contact one another throughout their entire side surfaces for the purposes described.

2. An artificial tooth attachment, comprising in combination, a tooth body the back of which is a flat surface which extends from the back edge of the attrition surface forward toward the cervical end of the tooth, each side of the tooth having a groove adjacent and substantially parallel to the front face of the tooth body, and from this groove to the back the sides of the tooth body are flat, and a plate of thin

sheet metal fitting against the flat back and the flat sides of the tooth the front edges of 15 the sides of which plate are turned inward to fit the grooves, and means for attaching this fastening to the structure by which the tooth is supported in the jaw.

In testimony whereof I affix my signature 20 in presence of two witnesses.

WILLIAM JAMISON CURRY.
